(57) **CLAIM**

I claim the ornamental design for a shoe sole tread, as shown and described.

DESCRIPTION

FIG. 1 is a bottom perspective view of a shoe sole tread. FIG. 2 is a bottom view of the shoe sole tread shown in FIG. 1.

FIG. 3 is a top view of the shoe sole tread shown in FIG. 1. FIG. 4 is a left side view of the shoe sole tread shown in FIG. 1.

FIG. 5 is a right side view of the shoe sole tread shown in FIG. 1. FIG. 6 is a front view of the shoe sole tread shown in FIG. 1; and,

FIG. 7 is a rear view of the shoe sole tread shown in FIG. 1.

The broken lines represent portions of the article and features of the environment that form no part of the claimed design.

1 Claim, 7 Drawing Sheets
